Specification for Design.

Patented Sept. 11, 1917.

Application filed July 26, 1917. Serial No. 182,988. Term of patent 3½ years.

To all whom it may concern:

Be it known that we, JAMES T. ROBB, a subject of the King of Great Britain, residing at Bay Shore, in the county of Suffolk, State of New York, and LORIN W. YOUNG, a citizen of the United States, residing at the borough of Manhattan, in the city, county, and State of New York, have jointly invented a new, original, and ornamental Design for a Portable Lamp, of which the following is a specification, reference being had to the accompanying drawing, forming part thereof.

The figure is an elevation of a portable lamp, showing our new design.

We claim:

The ornamental design for a portable lamp, as shown.

JAMES T. ROBB.
LORIN W. YOUNG.
